UNITED STATES PATENT OFFICE

EUGENE FARKAS, OF NEW YORK, N. Y.

CHANGEABLE EXHIBITOR

Application filed January 30, 1931. Serial No. 512,361.

The present invention relates to improvements in changeable exhibitors and particularly to the type, whereby a plurality of objects may be successively exposed to view, a part of one of the objects, however, being continually exposed to view, while the other part is alternately exposed to view at predetermined intervals.

An object of this invention resides in the provision of an exhibitor having two sets of relatively slidable display members, one set of display members being non-removable and causing a non-changeable exhibit, and the other set being removable and adapted for changing the exhibit.

Another object of this invention resides in the particular arrangement and structural features of the cooperating elements.

With these and other objects in view, the invention will hereinafter be more particularly described, and the combination and arrangement of parts will be shown in the accompanying drawings and pointed out in the claims which form part of this specification, it being understood that the embodiment herewith shown is merely illustrative and that various changes in the form, proportion, size and minor details of construction within the scope of the claims, may be resorted to without departing from the spirit of the invention.

Reference will now be had to the drawings, wherein like numerals of reference designate corresponding parts throughout the several views, in which:

Figure 1 is a front elevation of the device, the exhibit being a complete view of a clock and comprising the hands and the dial of the clock.

Figure 2 is a front elevation of the device, the exhibit comprising a complete view of an advertising poster and only the hands of the clock being visible—that is, an incomplete representation of the clock.

Figure 3 is a section taken on line 3—3 in Figure 1.

Figure 4 is a section taken on line 4—4 in Figure 2.

Figure 5 is a fragmentary portion of a slidable frame as shown in the lower position

in Figure 3, and carrying the non-removable exhibit members.

Figure 6 is a fragmentary portion of the slidable frame in the upper position.

Figure 7 is a cross section taken on line 7—7 in Figure 1.

Figure 8 is a cross section taken as on line 8—8 in Figure 2.

Figure 9 is a fragmentary side view of the main frame.

Figure 10 is a plan view of one of the non-slidable exhibit members forming the removable exhibit.

In the illustrated embodiment of the invention, the numeral 10 represents side wall uprights which are fastened to the casing 11 in any suitable manner, as by means of screws 12, 12. The uprights 10, 10 are provided with a plurality of angular extensions 13, 13, which are positioned relative to each other in series, in parallel planes, in angular relation with the vertical plane, and the adjoining ends of any two extensions of the series being in the same horizontal plane.

Each of the extensions 13 is provided with a projecting rivet 14, which is in alignment with a similar rivet 14, on the corresponding extension on the opposite upright 10, as best shown in Figure 7. Mounted on each pair of aligned rivets is one of the non-slidable exhibit members 15, best shown in Figure 10, each of said members having apertures 16, 16, therein, which are larger in diameter than the heads of the rivets 14, 14, and allow clearance for the heads to pass through and the said members to rest on the bodies of the rivets. Two elongated tubular slotted members 17, 17, are slidably mounted over and engage with the heads of all the rivets 14, 14, and lock the exhibit members 15, 15 in place.

The exhibit members 15, 15 are positioned relative to each other the same as the angular extensions 13, 13, and are provided on one side with the component parts of the representation of the advertising poster 18 shown in Figure 2. It is to be noted that the poster is cut up into a number of horizontal strips of a suitable height to fit and to be glued on to the non-slidable exhibit members 15, 15. The adjoining ends of any two of the exhibit

members 15, 15 are in the same horizontal plane and being very close to each other they present a display surface which appears to be unbroken and the completeness of vision of the displayed object is to all practical purposes substantially perfect.

Clock mechanism 19 is suitably concealed and supported within the casing 11 rearward of the exhibit members 15, 15, the hands 20 of the clock mechanism 19 extending in front of the exhibitor. The dial of the clock is temporarily not visible and there results at one period a partial exhibit of the clock and a full exhibit of the advertising poster, as best shown in Figure 2. At this point, the display surface discloses an incomplete representation of the clock and the effect produced on observers is to momentarily arrest their attention and to cause them to wait for the completion of the supplementary representation which consists of the dial of the clock. It is obvious that the hands 20 are continually actuated by the clock mechanism 19 within the casing and continually move over the display surface and indicate the correct time when supplemented by the appearance of the clock dial.

Slidably mounted within the casing 11, and rearwardly of the exhibit members 15, 15, are two upright guide rods 21, 21, having fixedly mounted at their lower ends two spaced horizontal beam members 22, 22, thus forming a rectangular frame 23. An electric motor 24, having a crank arm 25, is mounted in the casing 11 adjacent the frame 23. Rotatably mounted on the crank arm 25 is a roller 26, adapted to contact with the inner horizontal faces of the beam members 22, 22. When the motor is in operation, the roller 26 contacts with the lower beam member 22, and lowers the frame 23, to the position shown in Figures 3 and 5, and on the upward swing of the crank arm 25, the roller contacts with the upper beam member 22, and raises the frame 23, and the guide rods 21, 21. Fixedly mounted in spaced relation on the guide rods 21, 21, is a plurality of U shaped members 27, 27, positioned in parallel planes similar to the positions of the non-slidable exhibit members 15, 15, and adapted to cover and hide from view the advertising poster 18, as best shown in Figure 3. The U shaped members 27, 27, have their rearwardly positioned sides twice as long as the front sides and each member 27 is thus adapted to hide from view two exhibit members 15, 15. The exposed faces of the members 27 have painted or glued thereon the component parts of the representation of the dial 28 of the clock 19. The full representation of the clock is thus visible to the observer as shown in Figures 1 and 3.

It will thus be noted that when the motor 24 is in operation, the up and down motion of the frame 23, and the guide rods 21, 21,

will cause the U shaped members 27, 27, of the slidable exhibit to reciprocate up and down and to successively expose to view a plurality of objects, one of the objects being presented in an incomplete form at pre-determined intervals.

It will also be noted that while the embodiment herewith shows the changeable exhibitor when employing a clock or watch for the incomplete representation, that the hands and dials of electric measuring instruments or that of weighing scales may be used for this purpose.

It is readily apparent that the structure of my changeable exhibitor makes it possible to quickly remove the tubular lock members 17, 17, and the exhibit members 15, 15, and to substitute any other exhibit.

Having thus described my invention, what I claim as new and desire to secure by Letters Patent is:

1. In a changeable exhibitor having stationary and relatively slidable display members, the combination with upright frame members having angular extensions, a plurality of stationary display members detachably mounted on said extensions, said display members being positioned relative to each other in series, in parallel planes, in angular relation with the vertical plane, the adjoining ends of any two display members being in the same horizontal plane and presenting the component parts of the display as an unbroken unit, and a plurality of co-operating display members slidable relative to and alternately covering said stationary display members and forming a changeable exhibit.

2. In a changeable exhibitor having stationary and relatively slidable display members, the combination with two spaced upright frame members provided with angular extensions and with rivets having projecting heads, a plurality of stationary display members detachably mounted on said rivets, two elongated slit tubular members adapted to engage with the heads of said rivets and lock said display members in position, the adjoining ends of any two display members being in the same horizontal plane and presenting the component parts of the display as an unbroken unit, and a plurality of co-operating display members slidable relative to and alternately covering said stationary display members and forming a changeable exhibit.

3. In a changeable exhibitor having stationary and relatively slidable display members, the combination with two spaced upright frame members provided with angular extensions, a plurality of stationary display members detachably mounted in series on said extensions, two elongated slit tubular members adapted to engage with said projections and lock said display members in

position, a plurality of cooperating slidable display members mounted for reciprocation relative to and alternately covering said stationary display members, and means associated with said slidable display members for reciprocating the same.

4. In a changeable exhibitor having stationary and relatively slidable display members, the combination with two spaced side walls provided with extensions, a plurality of component stationary display members detachably mounted in series on said extensions, means for locking said component display members in position, a plurality of cooperating slidable display members mounted for reciprocation relative to and alternately covering said stationary display members, means associated with said slidable display members for reciprocating the same, and timepiece mechanism concealed interiorly of said exhibitor, the timepiece hands extending and being permanently visible in front of said exhibitor, and the said slidable exhibit consisting of the component parts of the timepiece dial.

5. In a changeable exhibitor having stationary and relatively slidable display members, the combination with a casing, two spaced uprights in said casing provided with extending arms, a plurality of stationary component display members mounted in series on said arms, means for securing said display members in position, a plurality of cooperating slidable display members mounted for reciprocation relative to and covering said stationary display members at intervals, means associated with said slidable display members for reciprocating the same, timepiece mechanism concealed interiorly of said casing, the timepiece hands extending and being permanently visible in front of said exhibitor and one of said exhibits consisting of the component parts of the timepiece dial.

6. In an advertising device having stationary and relatively slidable display members, the combination with two spaced uprights provided with extending arms, a plurality of stationary display members mounted on said arms, means for securing said display members to said extensions, a plurality of cooperating slidable display members mounted for reciprocation relative to said stationary display members, each of said slidable display members covering two stationary display members at predetermined intervals, means associated with said slidable display members for reciprocating the same, timepiece mechanism associated with said exhibitor, the timepiece hands being permanently visible in front of said exhibitor and one set of said display members representing the timepiece dial.

7. In an advertising device having stationary and relatively slidable display members, the combination with uprights provided with

extending arms, a plurality of stationary display members detachably secured to said arms, a plurality of slidable display members mounted for reciprocation relative to said stationary display members and being provided with power means for said reciprocation, timepiece mechanism incorporated with said device, the timepiece hands being permanently visible in front of said device and one set of said display members representing the timepiece dial.

Signed at New York City in the county of Kings and State of New York, this 28th day of January, A. D. 1931.
